US0D1063083S

(12) **United States Design Patent** (10) **Patent No.:** **US D1,063,083 S**
(45) **Date of Patent:** **** Feb. 18, 2025**

(54) **COMBINED DUAL ANKLE CUFF AND BAND**

(71) Applicant: **Shenzhen Rongqin Electronic Technology Co., Ltd.**, Shenzhen (CN)

(72) Inventor: **Haibin Huang**, Shenzhen (CN)

(73) Assignee: **Shenzhen Rongqin Electronic Technology Co., Ltd.**, Shenzhen (CN)

(**) Term: **15 Years**

(21) Appl. No.: **29/933,035**

(22) Filed: **Mar. 18, 2024**

(51) LOC (15) Cl. **24-02**

(52) U.S. Cl.

USPC **D24/192**

(58) **Field of Classification Search**

USPC D21/662, 683, 698, 797; D8/303, 330; D20/22; D29/113, 117.1, 120.1, 190, D29/791, 797; D24/190, 192

CPC ... A63B 69/0002; A63B 21/02; A63B 21/055; A63B 21/04

See application file for complete search history.

(74) Attorney, Agent, or Firm — Ricky Lam

(57) **CLAIM**

The ornamental design for a combined dual ankle cuff and band, as shown and described.

DESCRIPTION

FIG. 1 is a front perspective view of a combined dual ankle cuff and band, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is its usage state diagram; and,

In FIG. 10, the broken lines show two bands that depict environment and form no part of the claim.

FIG. 10 is its usage state diagram.

The broken lines representing stitching are part of the claimed design.

1 Claim, 10 Drawing Sheets
